DESIGN FOR A UTILITY CART

Alexander P. Fox, University City, and August Daniel Reisert, St. Louis, Mo., assignors to Lincoln Engineering Company, St. Louis, Mo., a corporation of Missouri

Application August 23, 1940, Serial No. 94,578

Term of patent 7 years

To all whom it may concern:

Be it known that we, Alexander P. Fox and August Daniel Reisert, citizens of the United States, and residents of University City, St. Louis County, Missouri, and St. Louis, Missouri, respectively, have invented a new, original, and ornamental Design for a Utility Cart, of which the following is a specification, reference being had to the accompanying drawings, forming part thereof, in which

Fig. 1 is a top plan view;

Fig. 2 is a front elevational view;

Fig. 3 is an end elevational view;

Fig. 4 is a rear elevational view;

Fig. 5 is an isometric view showing the front and one end; and,

Fig. 6 is an isometric view showing the rear and the other end of a utility cart, showing our new design.

We claim:

The ornamental design for a utility cart, substantially as shown.

ALEXANDER P. FOX.

AUGUST DANIEL REISERT.
